(57) **CLAIM**

The ornamental design for a translucent resin panel with faux stone pattern, as shown and described.

DESCRIPTION

FIG. 1 is a front perspective view of a translucent resin panel with faux stone pattern, showing usage in a partition structure;

FIG. 2 is a left side sectional view taken along line 2-2 of FIG. 3;

FIG. 3 is a front elevational view thereof;

FIG. 4 right side sectional view taken along line 4-4 of FIG. 3; FIG. 5 is a bottom plan sectional view taken along line 5-5 of FIG. 3; and,

FIG. 6 is a top plan sectional view taken along line 6-6 of FIG. 3.

The rear surface forms no part of the claimed design. The broken lines showing environment in the drawings are included for illustrative purposes only and form no part of the claimed design. The outer broken line boundaries in Figures depicting the boundaries of the claimed design indicate that a specific length, width, and thickness form no part of the claimed design and are for illustrative purposes only.
